R. NEISCH.

Limekiln.

No. 11,529.

Patented Aug. 15, 1854.

Inventor:
Robert Neigh.

UNITED STATES PATENT OFFICE.

ROBERT NEISCH, OF NEW YORK, N. Y.

LIMEKILN.

Specification of Letters Patent No. 11,529, dated August 15, 1854.

To all whom it may concern:

Be it known that I, ROBERT NEISCH, of the city, county, and State of New York, have invented certain new and useful Im-
5 provements in Limekilns; and I do hereby declare the following to be a full, clear, and exact description of the same, reference being had to the accompanying drawings, in which—

10 Figure 1, represents an elevation. Fig. 2, represents a vertical central section. Fig. 3, represents a horizontal section taken through the line E, E, of Fig. 2. Fig. 4, represents a horizontal section taken through 15 the line F, F, of Fig. 2. Figs. 5 and 6, are horizontal sections taken respectively at the lines C, C, and D, D, of Fig. 2, and Fig. 7, represents a section through the fire chamber hearth, ash-pit, and door for removing 20 the lime, and showing the construction of the arches over the fire chamber, the opening of the cupola, the fire passages, flues &c.

Similar letters in the several figures denote like parts.

25 The nature of my invention relates first, to the introduction of atmospheric air, to supply or aid combustion, from above the hearth and fire chamber. Also in the combination of the arched fire chamber, with the 30 inclined and curved hearth, for reflecting and concentrating the heat.

To enable others skilled in the art to make and use my invention I will proceed to describe the same with reference to the drawings.

35 The cupola may be constructed in any of the well known forms, gradually increasing in diameter from the top toward the bottom, until within about seven feet of the base, 40 and from that point gradually decreasing to the bottom.

The working of the kiln may be divided into three separate operations viz: the filling in, or charging of the cupola, the burning of the limestone, and the removing or drawing of the burnt lime. The manner of filling and drawing are well known, and need not be particularly described.

45 The bottom a', of the cupola, G whereon the burnt lime is continually burning, is so constructed as that the lime or burnt stone will slide toward the door a, from whence it can be readily removed when cooled. Two 50 separate iron doors prevent the atmospheric air from communicating with the interior 55 of the cupola G.

The burning of the stone is what I regard as the principal feature in my invention, and will confine my description more particularly to that part of it.

60 The fuel is fed into the fires through the doors or openings f the hearth or grate bars of which fires, are so inclined toward the center or rounded as to cause the fuel to fall together, where it is more readily raked and divested of the ashes, which are removed through the openings c' after they have become cool, and given up their heat to augment the fire, e' represents a supporting bar for sustaining the hearth in its center, and d are openings through which the fire may be regulated.

65 The heat arising from the burnt limestone lying in the bottom a', and the air which may find its way through the doors a, 70 is carried up through the flues b, b', underneath the grates or hearth, and thus furnishes heated air to promote the combustion. The first series of flues b, b', terminate in the ash box c, and then branch 75 off, as seen in Fig. 2, from the ash box, and lead to the fire, their entrance into the fire chamber being seen in Fig. 7. And when the burnt lime is drawn from a the flues b, b', may be closed up so as to prevent any 80 cold air from passing up to the fires, one of my main objects being to prevent the cold air from reaching the fires direct, without first passing in contact with the heated gases.

85 The principal part of the air required for supplying the fires is brought through the air flues g', and this I consider a leading feature in my invention. The usual practice is to bring the air for supplying combustion 90 underneath the hearth, and it enters the fire cold. By bringing it from above the hearth, the air is furnished in a heated state by coming in contact with the heated flame or gases before it reaches the center of combustion. The radiating heat is also gathered up by the cold air passing through the fire chamber to reach the fire, and this is due 95 somewhat to the construction of the fire chamber f. The burning up of the gases 100 and heated products is also more certain, because the flame is gaining time to complete perfect combustion, in passing through the openings f'', and through the fire passages h, and their openings h', to the interior 105 of the cupola G of the kiln, and here 110 comes in contact with the limestone.

The quantity of atmospheric air descending through the passage g can be regulated by a cap or register, as seen in Fig. 2, and marked g' . The fire passages h with their corresponding apertures h' extend up to about one third of the height of the stack or cupola G more or less, and are drawn together at the last opening in the passage i from whence four chimneys k with their opposite openings k' are built to the top of the cupola their tops being provided with caps for regulating the quantity of draft through them, said caps being represented at k'' Fig. 2. If found essential two or more passages such as at i might be made in connection with the fire passages h .

To make the cupola more secure and particularly to guard against expanding, cracking, or injury by the heat, a dead space m is formed between the inner and the outer wall l of the cupola which space may be filled with ashes, sand or some other non-conducting substance; or it may be an air space and unfilled, and in the latter case, the heat which might fill this dead space, can be if desired drawn into the cupola G . The same might be said of the so called dead space S , between both arches over the fire chamber f to permit the expansion of the

lower arch, and draw the heat to the cupola. 30 The parts of the wall marked m , are about three feet thick, and are bound into the outer and inner walls l , l' and thus give great strength to the whole kiln or stack. On the top of the cupola is a balustrade n , to protect the operator in filling in the stone. And to observe the progress of the burning of the limestone in the cupola G several holes marked o are left in the walls at various points. The whole kiln may also be 40 strengthened by binding it around with iron or wooden beams or bars p .

Having thus fully described the nature of my invention what I claim therein as new and desire to secure by Letters Patent is,— 45

1. In combination with the fire chamber f of the air conducting passage g for the purpose of bringing in the air from above the fire substantially as described.

2. I also claim in combination with the 50 arched fire chamber f , the inclined and curved hearth e , for concentrating the fuel and throwing the flame or heat toward the stack, substantially as described.

ROBERT NEISCH.
